UNITED STATES PATENT OFFICE.

SCOTT H. PERKY, OF SUMMIT, NEW JERSEY.

DESIGN FOR A CAKE OR SIMILAR PRODUCT.

Application filed May 1, 1922. Serial No. 2,025. Term of patent 14 years.

To all whom it may concern:

Be it known that I, SCOTT H. PERKY, a citizen of the United States, residing at Summit, in the county of Union and State of New Jersey, have invented a new, original, and ornamental Design for a Cake or Similar Product, of which the following is a specification, reference being had to the accompanying drawing, forming a part thereof.

The figure is a perspective view of a cake or similar product, constituting my new design.

I claim:

The ornamental design for a cake or similar product as shown.

SCOTT H. PERKY.
